UNITED STATES PATENT OFFICE

91,151

DESIGN FOR A BATHROOM SCALE

Harold L. van Doren, Toledo, Ohio, assignor to
Holley Manufacturing Company, Detroit, Mich.,
a copartnership composed of Earl Holley and
George M. Holley

Application September 18, 1933. Serial No. 49,285

Term of patent 14 years

To all whom it may concern:

Be it known that I, HAROLD L. VAN DOREN, a citizen of the United States of America, residing at Toledo, in the county of Lucas and State of Ohio, have invented a new, original, and ornamental Design for Bathroom Scales, of which the following is a specification, reference being had to the accompanying drawing, forming part thereof.

The figure is a perspective view of a bathroom scale, showing my new design.

I claim:

The ornamental design for a bathroom scale, as shown.

In testimony whereof I affix my signature.

HAROLD L. VAN DOREN.
